UNITED STATES PATENT OFFICE.

THOMAS OWEN, OF HOUSTON, TEXAS, ASSIGNOR OF ONE-HALF TO
JACOB V. DEALY, OF HOUSTON, TEXAS.

LOOSE-LEAF BINDER.

No. 834,163.

Specification of Letters Patent.

Patented Oct. 23, 1906.

Application filed January 4, 1906. Serial No. 294,610.

To all whom it may concern:

Be it known that I, THOMAS OWEN, a citizen of the United States, residing at Houston, in the county of Harris and State of Texas, have invented certain new and useful Improvements in Loose-Leaf Binders; and I do declare the following to be a full, clear, and exact description of the invention, such as will enable others skilled in the art to which it appertains to make and use the same.

This invention relates to improvements in loose-leaf binders for ledgers or other forms of books.

The object of the invention is to provide a simple, strong, durable, and efficient means by which the loose leaves may be quickly and easily attached to or removed from a book, said binders being so constructed as to permit the book to be opened out flat.

With the above and other objects in view the invention consists of certain novel features of construction, combination, and arrangement of parts, as will be hereinafter described and claimed.

In the accompanying drawings, Figure 1 is a plan view of an open book having the leaves thereof fastened by means of binders constructed and arranged in accordance with the invention. Fig. 2 is a sectional view through the same, showing the manner of securing the binders in place between the covers of the book. Fig. 3 is a detail perspective view of one end of one of the binders, showing the manner of fastening the leaves therein. Fig. 4 is a perspective view of an empty binder.

Referring more particularly to the drawings, 1 denotes the book having covers 2, between which are arranged a series of binders 3. The binders 3 each consists of a strip of thin flexible metal bent or folded longitudinally upon itself to form a V-shaped channel *a*, into which the inner ends of the leaves of each section are adapted to be inserted. On one edge of said folded strip or binder are formed two or more integral tongues 4, adapted to be inserted through aligned slits 5, formed in the leaves adjacent to their inner edges. Said tongues after being passed through the slits 5 are bent upon the opposite side of the binder, as shown, thus se-

curely holding the leaves in place in the binders. Adjacent to the folded edge of each of the binders are formed aligned slots 6, and through said slots is adapted to be inserted a binding-strip 7, which may be of any suitable material, but which is preferably formed of sheepskin or tough leather. The ends of the strip 7 project beyond the outer sides of the series of binders and are adapted to be secured in the covers of the book, as shown in Fig. 2, thereby securing said binders between the covers in the form of stubs.

By means of a binder constructed as herein shown and described any number of leaves 65 may be applied to a book, and said leaves may be inserted at any desired place in the book.

From the foregoing description, taken in connection with the accompanying drawings, 70 the construction and operation of the invention will be readily understood without requiring a more extended explanation.

Various changes in the form, proportion, and the minor details of construction may be 75 resorted to without departing from the principle or sacrificing any of the advantages of this invention as defined by the appended claim.

Having thus described my invention, what 80 I claim as new, and desire to secure by Letters Patent, is—

The herein-described loose - leaf binder comprising a strip of metal bent upon itself longitudinally to provide a V-shaped channel *a* to receive the leaves of a book, tongues 4 formed on one edge of said strip, said tongues being adapted to be inserted through slits formed in said leaves and to be bent down into engagement with the opposite 90 side of said metal strip, and flexible securing-strips 7 connected to the back of the book, said metal strip being provided with slots 6 through which the securing-strips 7 pass, substantially as described.

In testimony whereof I have hereunto set my hand in presence of two subscribing witnesses.

THOMAS OWEN.
